United States Patent Office

Des. 180,886
Patented Aug. 27, 1957

180,886

EXHAUST DEFLECTOR

Linus E. Russell, Springfield, Ohio

Application November 16, 1955, Serial No. 38,918

Term of patent 14 years

(Cl. D14—6)

Fig. 2

Fig. 3

Fig. 4

Fig. 1 is a perspective view of an exhaust deflector embodying my design;

Fig. 2 is a side view thereof;

Fig. 3 is an end view thereof; and

Fig. 4 is a bottom view thereof.

I claim:

The ornamental design for an exhaust deflector, substantially as shown.
